UNITED STATES PATENT OFFICE

156,294

DESIGN FOR A COMBINATION AIR BLOWER FOR ROOM HEATING AND COOLING

Richard A. Trow, Albert Lea, Minn., assignor to
Queen Stoves Works, Inc., Albert Lea, Minn., a
corporation of Delaware

Application April 24, 1948, Serial No. 145,941

Term of patent 14 years

(Cl. D62—4)

To all whom it may concern:

Be it known that I, Richard A. Trow, a citizen of the United States, and a resident of Albert Lea, in the county of Freeborn and State of Minnesota, have invented a new, original, and ornamental Design for a Combination Air Blower for Room Heating and Cooling, of which the following is a specification, reference being had to the accompanying drawing, forming part thereof:

Figure 1 is a perspective view of a combination air blower for room heating and cooling, showing my new design placed in one position for blowing air upwardly.

Figure 2 is a perspective view of the blower showing it mounted in another position for blowing air horizontally with the discharge grill portion positioned for deflecting the air downwardly, and

Figure 3 is an end elevational view of the blower. The reverse side of the blower is substantially similar to the side illustrated.

The dominant features of my design reside in the portions shown in full lines.

I claim:

The ornamental design for a combination air blower for room heating and cooling, substantially as shown and described.

RICHARD A. TROW.
